Primary Examiner — Nicole C Shiflet*Assistant Examiner* — Yen Le Southwood(74) *Attorney, Agent, or Firm* — QuickPatents; Kevin Prince(57) **CLAIM**

The ornamental design for a grilling pin, as shown and described.

DESCRIPTION

FIG. 1 is a top perspective view of a grilling pin, showing my new design with a pin in a locked position;

FIG. 2 is a top perspective view, illustrated with the pin in an unlocked position;

FIG. 3 is a front elevational view of FIG. 2;

FIG. 4 is a rear elevational view of FIG. 2;

FIG. 5 is a top plan view of FIG. 2;

FIG. 6 is a bottom plan view of FIG. 2;

FIG. 7 is a right-side elevational view of FIG. 2; and,

FIG. 8 is a left-side elevational view of FIG. 2.

The broken lines in FIG. 1 depict grilled food items that are environmental matter that forms no part of the claimed design.

1 Claim, 6 Drawing Sheets
